FOOT SWITCH

Charles Scott, 2144A W. Juno Ave., Orange, Calif.

Filed May 10, 1965, Ser. No. 85,199

Term of patent 14 years

(Cl. D26—13)

FIG. 1.

FIG. 2.

FIG. 3.

FIG. 4.

FIG. 5.

FIG. 7.

FIG. 6.

FIG. 8.

FIG. 1 is left side elevational view of a foot switch showing my new design;

FIG. 2 is a top plan view thereof wherein the foot switch has a single receptacle;

FIG. 3 is a front elevational view thereof;

FIG. 4 is a rear elevational view of the form of this foot switch having a single receptacle;

FIG. 5 is a top plan view of a foot switch showing a modified form of my new design wherein the foot switch has two receptacles;

FIG. 6 is a rear elevational view thereof;

FIG. 7 is a top plan view of a foot switch showing a modified form of my new design wherein the foot switch has three receptacles; and

FIG. 8 is a rear elevational view thereof.

I claim:

The ornamental design for a foot switch, substantially as shown and described.
